UNITED STATES PATENT OFFICE.

JOHN F. A. DECK, OF OKMULGEE, OKLAHOMA.

KNOCKDOWN CLAMP-TANK.

1,344,549.

Specification of Letters Patent. Patented May 25, 1920.

Application filed December 12, 1919. Serial No. 344,445.

To all whom it may concern:

Be it known that I, JOHN F. A. DECK, a citizen of the United States, residing at Okmulgee, in the county of Okmulgee and State of Oklahoma, have invented a new and useful Knockdown Clamp-Tank, of which the following is a specification.

This invention relates to the class of metallic storing and shipping vessels, and more particularly to improved tanks for storing oil or other liquids, the object thereof being to provide a novel tank of the knock down type, composed of a series of sections of metallic sheet metal plates joined together to provide a rigid container capable of being made in large sizes to resist considerable internal pressure.

A further object of the invention is to provide an improved clamp for connecting the sections of the tank, so that the same can be assembled with facility and when so assembled, will remain water proof or liquid tight against the escape of the contained fluid, and which will not only permit the tank to be manufactured economically but permit the parts to be produced and shipped to a desired point, where it is to be assembled, thereby lending efficiency in the field.

With the above and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings:

Figure 1 is a plan view of my improved knock down tank;

Fig. 2 is an elevation thereof;

Fig. 3 is a bottom plan view of the tank;

Fig. 4 is a sectional view at the top or rim of the tank, and showing the manner of joining the top and lateral section or side;

Fig. 5 is a sectional view taken on the line 5-5 of Fig. 2, and showing a clip or clamp in conjunction with the method of fastening the side plates together, and

Fig. 6 is a sectional view showing the manner of connecting the bottom and side.

As shown in the drawings, in which like reference characters designate corresponding parts throughout the several views, the tank is shown as comprising a lateral section or side 10 formed of a series of vertical plates 11 of the proper convexity, the same being of sheet metal and having their vertical side edges bent radially outwardly, as indicated at 12, substantially at right angles, and then circumferentially in opposite direction at right angles as indicated at 13, forming flanges by which the strips 11 constituting the lateral section or side of the tank, are secured together. The clips are indicated at 14, and are in the form of clamps comprising opposed jaws 15 and 16 substantially of rectangular cross section and slightly elongated. The jaw 15 is provided with a projection 17 in the form of a rib projecting from its inner face and extending longitudinally thereof to engage a groove 18 in the inner face of the jaw 16. These faces are also provided with coacting grooves 19 extending longitudinally thereof, these grooves or recesses 19, being designed to receive the flanges 13 after the flanges 12 have passed between the coacting inner faces of the jaws inwardly of the recesses 19, a suitable packing 20 of wire asbestos, mineral wool or the like being inserted between the outturned portions or flanges 12, so as to produce a liquid tight joint. A clamping member or bolt 21 is engaged through the coacting jaws, aligned apertures being provided therethrough for this purpose, so that the jaws can be tightly clamped together against the outturned portions of the plates or side sections 11, so as to rigidly connect the same, and prevent separation thereof. By this construction, the tank is permitted to withstand considerable outward pressure without permitting the joints to separate and thereby preventing the tank from leaking.

The clamps 14 are preferably disposed in spaced relation circumferentially of the tank body, and spaced also vertically at the joints between the sections or plates 11 and as shown in the drawings, the clamps are disposed in closer relative positions toward

the bottom of the tank, in order to permit withstanding of the increased pressure and weight against the lateral section or side at the bottom, as compared to the same at the 5 top portion of the tank.

The bottom of the tank is indicated at 22, and comprises an intermediate section 23 and substantially semi-circular sections 24 at either side thereof, having their peripheral edges conforming to the end edges of the intermediate sections 23, and having their sides, formed with flanges joined by clamps corresponding to the clamps 14, as already described. However, in order to 10 join the peripheral edges of the bottom to the lower edge of the lateral section or side of the tank, there are provided clamping members 25 of the same construction as the clamping members 14, except that the bottom and the side are arranged in contiguous relation to enter between the jaws 15 and 16. In other words the bottom is made of sufficiently larger diameter to be received between the jaws 15 and 16, and is then bent 15 upwardly at right angles, as indicated at 26, to enter one of the grooves or recesses 19, the same being formed in the jaw 16 as shown. The bottom edge of the side portion of the tank is bent outwardly at right angles 20 as indicated at 27, and upwardly as indicated at 28, at right angles to the portion 27, so as to co-act with the portion 26 and be retained from radial displacement, when the jaws are clamped together, with an intermediate packing 29, of the type heretofore 25 specified. It is also to be understood that the jaws are clamped together in the manner heretofore specified, thereby producing an effective connection at the edges so 30 joined.

The top or cover is designated at 30 and is formed of an intermediate section 31 and side sections 32, one of which may be provided with a suitable manhole 33, the cover 35 of which is indicated at 34 for obvious purposes. The co-acting edges of the sections 31 and 32 which engage each other, are connected by clamps, in the same manner as described in connection with the side of the 40 tank, and shown in Fig. 5 of the drawings. However, in order to connect the top or cover to the side of the tank, clamps 35 are employed, these clamps substantially corresponding to the construction of the clamps 45 14 and 25 and it is to be here noted that the rib or projection 17 may be of any desired cross section, while the inner wall of the groove or recess 18 may extend at an oblique angle from the end wall thereof, so 50 as to permit the necessary interfitting engagement of these parts, when assembling the abutting flanges at the edges of the plates and the packing, and joining the same, as specified. In joining the cover to the side, 55 the top edge of the side is bent outwardly

as indicated at 36 and then downwardly as indicated at 37 to enter one of the grooves 19, while the cover is extended sufficiently outwardly to enter between the jaws 15 and 16, and is then bent upwardly at right angles, to form a flange 38 to enter the opposed groove 19, the co-acting portions being clamped together, with or without the packing, as desired, although it is to be here stated that the packing is found unnecessary at the top. The cover is preferably braced by means of angle stiffeners 39 preferably extending diametrically at right angles to each other, and receiving through the center of the cover, a pipe column 40 passed to the means of supplying or draining the tank with or of the fluid contained therein and supported by series of brace rods 41 from the cover, which are preferably extended diagonally between said pipe and the cover and composed of threaded sections connected by turn buckles 42, in order that the pipe can be properly supported in position.

Thus, it will be readily seen that the parts of the tank can be shipped, knock down and clamped together in the field or wherever the device is designed to be used for containing oil or other liquids. This provides means whereby the tank can be very economically produced and set up, insuring efficiency in the field, and resulting in a tank structure which is particularly strong and sealed against leakage. The parts may be readily assembled and clamped together to form the complete structure, without employing skilled labor.

Having thus described my invention what I claim is:

1. A knock down clamp tank comprising a lateral section, and end sections each comprising a series of sheet metal sections having their meeting edges provided with flanges, at least one of said end sections comprising an intermediate sheet metal section with convexed ends and rectilinear side edges and semi-circular sections at either side thereof and coöperating therewith to produce a circular member, said semi-circular sections having rectilinear edges abutting the aforesaid rectilinear edges, said edges being provided with flanges and clamping means for connecting said sections at the flanges, said clamping means comprising coacting jaws provided with registering recesses for receiving said flanges and adapted to clamp the sections inwardly of said recesses, means for preventing relative movement of the jaws facewise but adapted to permit angular engagement and disengagement thereof, and means between the recesses and the last-named means for clamping the jaws together.

2. A knock down clamp tank comprising a lateral section, a bottom, a cover, each

comprising a series of sheet metal sections having their meeting edges provided with flanges, and clamping means for connecting said sections at the flanges, said clamping 5 means comprising co-acting jaws, means to hold the jaws against relative movement facewise or lengthwise, said jaws being provided with grooves for receiving said flanges, packing means between certain of 10 said sections at the flanges and between the jaws, and means for clamping said jaws together.

3. A knock down clamp tank for containing oil or the like, comprising a lateral section 15 formed of a series of strips of sheet material disposed with their edges in abutting relation and formed with right angularly bent portions substantially parallel thereto, a bottom for the tank, and clamps 20 for connecting said right angularly bent portions with an intermediate packing, said clamps comprising jaws having recesses receiving said portions and clamping the same together between the recesses and the inner 25 edges of the jaws against the strips, one of said jaws being provided with a rib and the other provided with a recess engaged by the rib at their co-acting faces, and clamps 30 passed through the jaws.

30 4. A knock down clamp tank for containing oil or the like, comprising a lateral section formed of a series of strips of sheet material disposed with their edges in abutting relation and formed with right angularly 35 bent portions substantially parallel thereto, a bottom for the tank, and clamps for connecting said right angularly bent portions with an intermediate packing, said clamps comprising jaws having recesses receiving 40 said portions and clamping the same together between the recesses and the inner edges of the jaws against the strips, and means for holding said jaws together in clamping relation to the angularly bent portions, said jaws being held from turning 45 one relative to the other, and said clamps being disposed in spaced relation.

5. The combination with relatively flat sheet metal sections adapted to be secured 50 together at their edges and provided with flanges bent in angular relation with respect thereto; of clamping means therefor, said clamping means including jaw blocks disposed in contact and provided with coacting 55 grooves extending across the same and receiving said angularly bent portions in opposite directions, said jaw blocks clamping said sections inwardly of said grooves, said angularly bent portions being designed to 60 receive a packing therebetween, one of said jaw blocks having a recess across its inner face adjacent to its outer end and the other jaw block having a rib across its inner face engaging said recess, and adjustable clamp- 65 ing means disposed through the jaw blocks

between the grooves and said coacting rib and recess.

6. A clamp of the class described comprising co-acting jaw blocks, said jaw blocks being provided with co-acting registering 70 recesses in their inner faces adapted to receive angularly bent portions of a plurality of abutting sheet metal sections therein and to clamp said sections inwardly of said recess, said jaw blocks having aligned openings 75 therethrough intermediately of their ends, one of said jaw blocks being provided near its outer end with a groove across its inner face and the opposed jaw block having a rib across its inner face engaging said 80 groove, and a connecting member for the blocks passing through said openings between the recess and the coacting groove and rib.

7. The combination with sheet metal sections adapted to be secured in abutting relation at their edges and provided with flanges bent outwardly and then laterally in parallel relation to said sections; of clamping means therefor, said clamping means including rectangular jaws disposed in contact and with their inner edges abutting the sections and receiving said outwardly extended portions therebetween, said jaws being provided with opposed registering recesses 95 extending longitudinally thereof spaced from the inner edges thereof and receiving said laterally bent portions, packing means between said outwardly bent portions, said jaws being provided with aligned 100 transverse apertures, and a bolt passed through apertures for clamping said jaws.

8. The combination with sheet metal sections adapted to be secured in abutting relation at their edges and provided with flanges bent outwardly and then laterally in parallel relation to said sections; of clamping means therefor, said clamping means including rectangular jaws disposed in contact and with their inner edges abutting the 105 sections and receiving said outwardly extended portions therebetween, said jaws being provided with opposed registering recesses extending longitudinally thereof spaced from the inner edges thereof and receiving said laterally bent portions, packing means between said outwardly bent portions, said jaws being provided with aligned 110 transverse apertures, one of said jaws being provided with a longitudinal groove and the other of said jaws being provided with a longitudinal rib engaging in said groove to hold said jaws being provided with a longitudinal rib engaging in said groove to hold 115 said jaws in alignment, and means to connect and clamp said jaws together.

9. A clamp for the purposes set forth, comprising coacting rectangular blocks of elongated formation, said blocks forming jaws and having aligned transverse openings 30

therethrough intermediately of their ends, one of said jaws being provided near its outer edge with a rectilinear groove in its inner face and the inner face of the opposed jaw being provided with a rectilinear rib snugly fitting said groove, said jaws near their inner edges being provided with opposed recesses at their inner faces, and a bolt connecting said blocks through said

openings therein for clamping the same together.

In testimony that I claim the foregoing as my own I have hereto affixed my signature in the presence of two witnesses.
